(57) **CLAIM**

The ornamental design for a camera portion of a portable telephone, as shown and described.

DESCRIPTION

FIG. 1 is a front elevational view of a camera portion of a portable telephone, showing our new design;

FIG. 2 is a rear elevational view thereof;

FIG. 3 is a top plan view thereof;

FIG. 4 is a bottom plan view thereof;

FIG. 5 is a left side elevational view thereof;

FIG. 6 is a right side elevational view thereof; and,

FIG. 7 is an enlarged cross-sectional view thereof, taken along line 7—7 of FIG. 1, with the internal system omitted. The broken lines in all views are shown for illustrative purposes only and form no part of the claimed design
